ULTRA HIGH FREQUENCY OSCILLATOR

Palmer H. Craig, Gainesville, Fla., assignor to
Invex, Inc., a corporation of Florida

Application October 18, 1944, Serial No. 559,215

4 Claims. (Cl. 315—4)

1

This invention relates to an electronic oscillator capable of generating oscillations of ultra-high frequency.

An object of the invention is to devise an electronic oscillator in which the frequency of the oscillations is dependent upon the speed of the electrons and is not determined by resonance of a circuit.

The invention involves an electron tube in which a concentrated beam of electrons is projected through a series of aligned inductor elements each of which embodies a pickup coil. The electron stream is interrupted or varied periodically so that groups or bunches of electrons pass in succession through said inductor elements. A voltage impulse of one polarity is generated in each coil by each group of electrons approaching the inductor, and an impulse of opposite polarity is generated as each electron group recedes from the inductor. The pickup coils are connected in a common output circuit and a feedback connection is provided from the output circuit to control the phase relation of the grouping or bunching of the electrons in the stream in order to secure maximum amplitude of the voltages induced in the pickup coils.

My invention is illustrated in the accompanying drawing in which

Figure 1 is a diagrammatic representation of the preferred form of the oscillator circuit, the electron tube being shown in longitudinal cross-section;

Figure 2 is a sectional view of the magnetic core of an inductor element showing various dimensions and factors controlling the operation of the oscillator; and

Figures 3 and 4 are diagrams illustrating the voltages induced in the inductor elements.

Referring to the drawing, the electronic tube employed in the oscillator is diagrammatically represented in Figure 1 and may consist of an insulating envelope 1 containing a suitable cathode 2 mounted in one end thereof and heated from a suitable source 3. An anode or plate P is mounted in front of the cathode and is provided with a central aperture or opening Pa. A control grid G is interposed between the cathode 2 and the plate P which plate is maintained at a positive potential with respect to cathode 2 by a suitable source 4. A second anode 5 is provided in the opposite end of the tube from cathode 2 and may form the end wall of the tube as shown in Figure 1 or it may be separate from the end wall if desired. This anode is maintained at a positive potential with respect to

2

plate P by means of source 6. Interposed between plate P and anode 5 is a series of inductors embodying magnetic rings 7 arranged in axial alignment with the aperture Pa in the plate P and being spaced apart at regular intervals. Each magnetic ring may be formed of compressed powdered Permalloy, Mu-metal, or other suitable magnetic material and carries a pickup coil 7a. These pickup coils are connected in serial circuit relation in an output circuit which supplies a load device 8. An oscillator 9 of suitable construction is connected to supply a control wave to control grid G, and the oscillator is controlled or synchronized and properly phased with respect to the oscillations in the output circuit by means of a feedback circuit including a phase shifting filter 10 of suitable construction. In the example shown in Figure 1, the filter may be formed of two series condensers 10a and 10b in opposite sides of the feedback connection and a variable shunt resistance 10c. The function of control grid G is to break up the electron stream passing through the inductor elements into groups or bunches of electrons, and for this purpose I prefer to use an oscillator at 9 producing a square-top wave, although other wave shapes may be employed. A suitable form of oscillator to be used at 9 will be found in "Terman's Radio Engineering Handbook" at pages 970 and 971.

Operation of Figure 1 is as follows: The electrons emitted from cathode 2 are drawn towards the plate P by source 4 and the velocity of the electrons passing through the aperture Pa will be determined by the voltage of the plate P with respect to the cathode 2. Suitable focusing coils or electrodes may be used to concentrate the electrons on the aperture Pa if desired. The grid G serves to interrupt or vary the stream of electrons which passes through the aperture Pa so that the stream passing through the aperture is formed of a series of successive groups or bunches of electrons which are projected along the common axis of the inductor rings 7. If desired, conventional electron focusing coils or electrodes may be employed to concentrate and direct the stream along the axis of the inductor elements. As each electron group or bunch approaches and passes through each inductor, a complete cycle of voltage is generated in the associated pickup coil 7a, and the duration of the induced cycle will be dependent upon the speed at which the electron bunch is travelling. Since all of the pickup coils are connected to a common output circuit, each bunch of electrons will induce a voltage cycle in each pickup coil as

it passes from plate P to anode 5. In other words, in the example shown in Figure 1, each bunch of electrons will induce ten complete cycles of voltage in the output circuit in passing from plate P to anode 5, and the separation between the successive cycles of voltage will be dependent upon the speed at which the electron bunch is travelling and upon the distance of separation between adjacent inductor units. Accordingly, by properly spacing the inductor units and by adjusting the speed of the electrons, the frequency of the voltage impressed upon the output circuit may be controlled. With a given spacing between the inductor units, the frequency may be varied by varying the voltage of the source 4 or of the source 6 or of both.

In order that the succeeding bunch or group of electrons shall have the proper phase relation to augment the voltage induced by a given bunch of electrons, it is important that the groups or bunches of electrons shall be released by the grid G in a predetermined phase relation with respect to the oscillations in the load circuit. For this

$$\begin{aligned} \text{E. M. F.} &= -N \frac{d\phi}{dt} = -N \frac{d\phi}{dx} \frac{dx}{dt} = -N \frac{d\phi}{dx} V \\ &= -NV^2 Qu \frac{d \left(\sinh^{-1} \frac{x+b}{y-a} - \sinh^{-1} \frac{x-b}{y-a} - \sinh^{-1} \frac{x+b}{y+a} + \sinh^{-1} \frac{x-b}{y+a} \right)}{dx} \\ &= -NV^2 Qu \left[\frac{1}{(y-a)^2 + (x-b)^2} - \frac{1}{(y-a)^2 + (x+b)^2} + \frac{1}{(y+a)^2 + (x+b)^2} - \frac{1}{(y+a)^2 + (x-b)^2} \right] \end{aligned} \quad (5)$$

purpose, a feedback circuit including phase shifter 10 is provided for controlling the phase relation of the pulses generated by control generator 9 in timed relation with the oscillations in the load circuit. The proper phase relation may be secured by adjusting the values of the elements in phase shifter 10 until maximum output is obtained in the load circuit.

Since energy will be absorbed from each electron charge or group as it passes through each inductor element, the speed of the charge will be slowed down, and in order to compensate for this loss in velocity, the anode 5 is maintained at a positive potential with respect to plate P by means of source 6. Additional accelerator anodes (perforated anodes) may be inserted at different points along the series of pickup units in order to compensate for the loss in energy, and these additional anodes would be connected to intermediate points on the source 6. One such accelerating anode is shown at 5'.

The wave form of the electromotive force which is induced in each pickup coil may be understood from the following. Referring to Figure 2, if Q represents a charge moving at a given velocity V along the axis of magnetic ring 7, then the field H of this moving charge at the point S located at a distance r from Q and at an angle θ with respect to V may be determined from the following equation:

$$H = VQ \sin \theta / r^2 \quad (1)$$

In Figure 2 the point S has been taken at the center of the magnetic path of the ring 7 which has a cross-section of $2b \times 2a$ and a mean diameter of $2y$. The charge Q is located at a distance x from the central plane of the ring 7 passing through the point S. The flux ϕ induced in the ring by the field H will be:

$$\phi = \mu H da \quad (2)$$

where μ is the permeability of the ring.

Since the magnetic circuit of ring 7 is uniform in cross-section and is symmetrical about the axis of the ring, Equation 1 may be stated in terms of a, b, x and y as follows:

$$H = \frac{VQ \frac{y}{\sqrt{x^2+y^2}}}{x^2+y^2} = VQ \frac{y}{(x^2+y^2)^{3/2}} \quad (3)$$

The total flux induced in the magnetic circuit of ring 7 now becomes:

$$\begin{aligned} \phi &= \frac{VQu}{2} \int_{x-b}^{x+b} \int_{y-a}^{y+a} \frac{2y}{(x^2+y^2)^{3/2}} dy dx \\ &= \left[\sinh^{-1} \frac{x}{y-a} - \sinh^{-1} \frac{x}{y+a} \right]_{x-b}^{x+b} uVQ \\ &= VQu \left[\sinh^{-1} \frac{x+b}{y-a} - \sinh^{-1} \frac{x-b}{y-a} - \sinh^{-1} \frac{x+b}{y+a} + \sinh^{-1} \frac{x-b}{y+a} \right] \end{aligned} \quad (4)$$

The electromotive force induced in any pickup loop wound around ring 7 will be:

From Equation 5 it will be seen that the induced voltage varies as the square of the velocity of the approaching charge, and directly with the value of the charge, the number of turns on a pickup coil, the permeability and dimensions of the inductor core, and the instantaneous position of the charge along the inductor axis.

Upon examining the term within the brackets and designating it as F(x), it will be found that as x is varied, the general shape of this function is shown in Figure 3. This figure also represents the shape of the induced electromotive force. As the charge Q approaches the magnetic ring from the left, the induced E. M. F. in the pickup coil increases to a maximum at a definite distance $-x_m$ from the center of the magnetic ring, and then reduces in value to zero at the plane of the ring and thereafter increases to a maximum value in the opposite direction at $+x_m$, and then decreases towards zero as the charge continues to the right of the ring along the axis.

Where several of the inductors are connected in series and are spaced apart by equal distances, the individual voltage cycles generated in the different coils are represented by the solid line curves in Figure 4, and the resultant alternating voltage produced by a group of electrons passing through the four coils is represented by the dotted line curve in this figure.

If more than one group of electrons is passing through the series of pickup units at the same time, the resultant voltage induced in the circuit will depend upon the relative spacing of the groups. It is important therefore that the spacing or phasing of the electron groups be properly controlled. The groups should be released in timed relation such that they are separated by a distance equal to the spacing between adjacent units or any multiple of this spacing. The proper phasing of the electron groups or bunches is determined by the phase shifter 10. The frequency of the electron groups, or the number of

groups per second which pass through aperture P_a , may be equal to the frequency of the generated voltage in the load circuit, or it may be any sub-multiple of this frequency.

The value of the resultant voltage generated in the series of pickup coils will also be dependent upon the length of each electron group or bunch passing through the series of pickup units. For most efficient operation the electron groups should have a length equal to half the distance of separation of adjacent pickup units. Other lengths are possible, but it is preferred to have the electron groups of a length of one-half the distance of separation between adjacent pickup units or an odd multiple of this length. The importance of the length of the electron group will become apparent when it is considered that the approaching end of the group induces a pulse of one polarity in a given inductor unit while the receding end of the group induces a pulse of opposite polarity in the same unit. The length of the individual electron groups or bunches will be determined by the shape of the control wave applied to the grid G from the source 9 .

The length of the inductor element along the electron path is also a factor in the shape of the current pulse generated in the pickup coils. Preferably, the inductor elements have a relatively narrow dimension in the direction of the electron stream with respect to the length of the path between the plate P and the anode 5 , and the inductor elements should not have a width along this path greater than one-half the distance of separation of adjacent units.

A condenser 11 may be connected across the load circuit to form a resonant combination with the pickup coils. This will reduce the effect of the inductance of the pickup coils in the output circuit. If desired, small condensers may be connected in series with the circuit between the inductor elements, or the condensers may be connected in parallel with the pickup coils. Such condensers may be located either inside of the tube or outside and would serve to tune each coil or a group of coils to a particular frequency. Furthermore, it is not essential that the pickup coils be connected in serial circuit relation to the output circuit, but they may be connected in parallel relation to the output circuit.

An amplifier may be inserted in the feedback connection either in front of or behind the phase shifter 10 , or the necessary amplification may be obtained in the control generator 9 .

It will be obvious that the details of construction of the oscillator tube may be varied in different ways. For example, instead of forming the inductor elements of magnetic rings with pickup coils wound thereon, these elements may be formed without magnetic cores and the pickup coils would surround the path of the electron groups and would be spaced apart in the same manner as the magnetic rings. Also, the pickup elements may be spaced apart by progressively decreasing distances in order to compensate for the loss in velocity of the electron groups as they move from the beginning towards the end of the series.

I claim:

1. An electronic oscillator comprising, in combination, a source of electrons, means acting on said source and producing a stream of electrons therefrom directed along a predetermined path, means periodically interrupting said stream to form a succession of electron groups along said path, a plurality of separate inductor elements mounted in spaced relation along said path and in inductive relation to said electron stream, each of said inductor elements including a coil, and an output circuit including said coils connected therein in series relation.
2. An electronic oscillator comprising in combination, a source of electrons, means producing a stream of electrons from said source and directed along a predetermined path, means periodically interrupting said stream to form a succession of electron groups along said path, said groups being of uniform lengths, a plurality of inductor elements mounted in spaced relation along said path and in inductive relation to said electron groups passing along said path, each inductor element including a coil, said inductor elements being spaced apart by distances of the order of twice the length of an electron group, and an output circuit having said coils connected therein in series circuit relation.
3. An electronic oscillator according to claim 1 wherein said inductor element comprises a magnetic ring surrounding said path, and a pickup coil wound on said ring.
4. An electronic oscillator comprising in combination, a source of electrons, means producing a stream of electrons from said source and directed along a predetermined path, means periodically interrupting said stream to form a succession of electron groups along said path, a plurality of inductor elements mounted in spaced relation along said path and in inductive relation to the electron stream, each of said inductor elements including a coil, an output circuit including said coils connected in series relation, and a feedback connection from said output circuit to said interrupting means for controlling the phasing of said interrupting means.
